(75) Inventor: **Russell G. Larsen**, San Jose, CA (US)

Primary Examiner—Joel Sincavage

(73) Assignee: **TVM Group, Inc.**, Fremont, CA (US)

(74) *Attorney, Agent, or Firm*—Flehr Hohbach Test Albritton & Herbert LLP

(**) Term: **14 Years**

(57) **CLAIM**

(21) Appl. No.: **29/140,710**

The ornamental design for a pin connector with central power pins, as shown and described.

(22) Filed: **Apr. 23, 2001**

DESCRIPTION

(51) **LOC (7) Cl.** **13-03**

FIG. 1 is a perspective view of the pin connector with central power pins of my new design.

(52) **U.S. Cl.** **D13/147**

FIG. 2 is a top plan view of the pin connector with central power pins shown in FIG. 1.

(58) **Field of Search** D13/147; 439/378, 439/677-680, 752

FIG. 3 is a bottom plan view of the pin connector with central power pins shown in FIG. 1.

(56) **References Cited**

FIG. 4 is a front elevational view of the pin connector with central power pins shown in FIG. 1.

U.S. PATENT DOCUMENTS

FIG. 5 is a rear elevational view of the pin connector with central power pins shown in FIG. 1.
